UNITED STATES PATENT OFFICE.

CHRISTOPHER M. SPENCER, OF HARTFORD, CONNECTICUT, ASSIGNOR TO THE NEW BRITAIN MACHINE COMPANY, OF NEW BRITAIN, CONNECTICUT, A CORPORATION OF CONNECTICUT.

COMBINED FORMING AND CUT-OFF TOOL.

1,223,438.

Specification of Letters Patent.

Patented Apr. 24, 1917.

Application filed September 18, 1916. Serial No. 119,865.

To all whom it may concern:

Be it known that I, CHRISTOPHER M. SPENCER, a citizen of the United States, residing at Hartford, in the county of Hartford and State of Connecticut, have invented certain new and useful Improvements in Combined Forming and Cut-Off Tools, of which the following is a specification.

This invention relates to a combined forming and cut off tool, the object being to provide an article of this character which is effective and accurate in action. The tool may be advantageously mounted in or employed in conjunction with metal-working and other machines of various kinds, one illustration being wherein the stock is in the form of a length or bar which is generally rotated during the forming and cutting off operations and at the conclusion of which the stock is released and then advanced for a repetition of such operations. The forming portion of the tool may be utilized in different ways, it being of particular utility, however, when employed for chamfering. This is but one example of several.

In the drawings accompanying and forming part of the present specification I have shown in detail one convenient form of embodiment of the invention which will be set forth fully in the following description. As may be inferred I do not restrict myself to this disclosure; I may depart therefrom in several respects within the scope of the invention defined by the claims following said description.

Referring to said drawings:

Figure 1 is a side elevation and

Fig. 2 a transverse section on the line 2—2 of Fig. 1, looking in the direction of the arrow, of a metal-working machine equipped with a tool embodying the invention.

Fig. 3 is a face view of the tool.

Fig. 4 is a bottom plan view of the same showing by dotted lines a head and the work.

Fig. 5 is a view of the tool as seen from the left in Fig. 3.

Fig. 6 is a practically similar view of the cutting portion merely of the tool.

Like characters refer to like parts throughout the several views which are on different scales; for instance Fig. 6 is on a larger scale than Figs. 3 to 5 inclusive, while the scale

of Figs. 1 and 2 is very much smaller than that of said Figs. 3 to 5.

As I have practically already observed, while the tool is of general use, it is of especial facility when mounted in a metal-working machine. In Figs. 1 and 2 I have shown parts of such a machine comprising the base or bed 2. Fastened as by bolts to the base or bed 2 is a bracket as 3, constituting a suitable support for a work-carrier as 4. The work-carrier is represented as consisting of a cylindrical member bored for the reception of a spindle 5 which is rotated in any way common in the art and which is provided at its front end with a collet which is closed and opened as occasion requires. In the present case the work rotates, although this might not always be necessary. During its rotation it is subjected to the action of the compound tool, a piece of stock forming an article or a blank for an article being cut off at the conclusion of such action. At this point the collet is opened and the stock advanced to bring into the range of action of the tool a second length of stock, at which time the operation is repeated.

The carrier for the tool hereinafter more particularly described, may be of any suitable nature, the slide 6 answering satisfactorily in this connection, having suitable means also hereinafter described to which the tool is connected. The slide in turn may be operated in any desirable manner as by the cam 7 carried by the shaft 8 which is given intermittent rotary movements as also common in metal-working and like-functioning machines. Supported by the bed 2 between its ends is a lever as 9 serving as a convenient means to transfer the effect of the cam to the slide, the upper end of the lever being pivoted or otherwise suitably jointed to the slide 6 and the lower branch having a stud as 10 extending into a race 11 of the cam, the construction being such that on each intermittent rotation of the cam the slide will be given a complete reciprocation to impart an advancing movement to the slide from its retracted position indicated in Fig. 2, the tool on the slide performing its offices on the advance motion of the slide. When the stock is cut off as will hereinafter appear the slide is retracted. I have de-

scribed but briefly certain elements of a metal-working machine. The invention, as will be clear, is not restricted in this particular.

5 As will be understood from the remarks already made the tool comprises a forming portion and a cutting off portion. Obviously the cut off portion is for cutting a piece of stock from the remainder. The 10 forming portion may be utilized in any desirable manner. In the present case it is adapted for chamfering, and the chamfered or otherwise-formed part cut off from the stock may be a nut, a nut blank or any other 15 suitable article. The work which the tool is assumed to do in the showing made is a nut or a nut blank, the stock in this particular case being hexagonal in cross section but as will be evident, the invention is not 20 limited in this and like particulars. There is in use a compound tool which is adapted to effect simultaneously forming and cut off functions, but the forming part of the tool concludes its office before the stock is 25 cut off, which is an objectionable factor, in that there is a protrusion or a bur left on the theoretically-finished face of the article. By my tool this thing is eliminated, the result being that the finished surface of the 30 article either in complete or blank form is smooth and clean. In the present device the forming action and the cutting action may occur and do occur contemporaneously, but the forming portion whether chamfering 35 or otherwise, is concluded before the cut is done, the result being the high grade of work noted. I show in detail in Figs. 3 to 40 6 inclusive a highly-advantageous structure by which the advantage in question can be accomplished, but I do not, except as demanded by the scope of my claims, restrict myself to any specific disclosure.

The tool illustrated especially in these 45 views and also appearing on a smaller scale in Figs. 1 and 2, involves in its organization a mounting part or member, the approximately flat shank answering satisfactorily in this particular. This shank when the 50 tool is used as represented in said Figs. 1 and 2 extends transversely of the bed 2 and is sustained by adjuncts on the slide, for instance it can be held fixedly in a clamp such as that denoted in a general way by 55 13. As shown the inner end of this shank has a laterally offset head 14 to which the tool members or portions are connected. There are two of such tool members or portions such as 15 and 16, the part 15 serving 60 as a chamfering element, while the part 16 acts to cut off. These two elements are practically circular in shape, the part 15 fitting flatwise against the laterally offset head 14 and being in turn countersunk as 65 at 17 on its outer face to receive for turning movement the part 16, both said parts

15 and 16 as will hereinafter appear being capable of rotary adjustment. The two parts may be associated together and connected with the mounting or equivalent part 12 in any desirable manner, although the 70 means shown for this purpose will now be described. The said parts 15 and 16 are centrally perforated to receive the headed stud 18 which also extends through a perforation or hole in register with the perforations or holes of said tool parts 15 or 16. The portion of the stud which extends into the opening of the head 14 is polygonal in cross section, the opening which receives said polygonal portion being correspondingly formed to prevent turning of the stud with respect to the head 14. The perforations or holes in the parts 15 and 16 are circular to comparatively freely receive the cylindrical portion of the stud 18. The back 75 end of said stud is threaded to receive the binding nut which can be operated to solidly flatwise clamp the tool parts 15 and 16 to each other and to the head 14. By loosening the nut either or both of the parts 15 and 16 can be rotatively adjusted, and when the adjustment is obtained the nut will be set to maintain the adjustment. The peripheral portion of the chamfering member 15 is cut away as at 20 to produce a 80 circumferential slot, one wall of the slot being upon a bevel as at 21, this beveled surface being intended for chamfering and having at one end a slight lip 22 to make an initial cut on the work.

The cutting off portion 16 has a peripheral slot 23, one wall of which or that denoted by 24 acting as the cutting off part of the tool. It will be noted, for instance on inspection of Fig. 3, that the cutting surface 24 is radial to the stock, while the cutting surface 21 is tangential to said stock. It will also be observed that the chamfering portion of the tool acts in advance of the cutting portion, the consequence being that the chamfering operation will be concluded before the cutting operation.

It will be assumed that the slide 6 is in its retracted position as shown in Fig. 2, 110 that the shank is clamped to said slide by the clamp 3 and that the work in the spindle 5 is held against longitudinal movement but is being rotated in the direction of the curved arrow. It will be further supposed that the slide 6 is advanced by the rotation of the cam 7. The slide on its advance follows the direction of the straight arrow in said Fig. 2. On the advance of the slide the tip or point 25 of the chamfering part 15 115 will meet the outer surface of the work and as the slide 6 continues to advance the chamfering operation will be commenced and will be finished slightly before the slide has completed its advance movement at which point 120 125 130

the slide is retracted. After the chamfering point or tip 25 has entered the stock, the point 26 of the cutting off member 16 will engage the stock, this as will be clear, occurring 5 during the advance of the slide. For a portion of said advance the two portions 15 and 16 will be simultaneously acting. Near the conclusion of said advance movement, however, the chamfering portion will 10 have completely finished its work. Beyond this point or after the chamfering portion has completed its function, the cutting off part 16 will continue to act and will finish its cut as the slide finishes its advancing 15 movement.

By the adjustment of the portions or parts 15 and 16 together or separately, the tool is adapted to articles of various shapes and sizes.

20 What I claim is:

1. A tool of the class described having forming and cut off portions to operate respectively tangentially and radially of the stock, the forming portion being adapted to 25 conclude its action before the action of the cut off portion is concluded.

2. A tool of the class described having chamfering and cut off portions to act respectively tangentially and radially of the stock, the chamfering portion being adapted 30 to conclude its action before the action of the cut off portion is concluded.

3. A tool of the class described having a 25 sectional circular part the sections of which are respectively provided with forming and cut off portions, the forming portion extending a greater distance away from the axis of

said circular portion than the cut off portion.

4. A tool of the class described having two 40 disks fitted together, each disk having a cutting edge shaped for forming and cutting off operations, the cutting edge of the forming disk being adapted to finish its action before the action of the other portion is 45 concluded.

5. A tool of the class described having two disks fitted together, each disk having a cutting edge shaped respectively for forming and cutting off operations, the cutting edge 50 of the forming disk being adapted to finish its action before the action of the other portion is concluded, the two disks being coaxial and rotatively adjustable.

6. A tool of the class described having 55 forming and cut off portions, the forming portion being adapted to conclude its action before the action of the cut off portion is concluded, and the two portions being adapted to act approximately in the same 60 plane at right angles to the axis of the stock.

7. A tool of the class described having forming and cut off portions, the forming portion being adapted to conclude its action before the action of the cut off portion is 65 concluded, the two portions being in superposed relation.

In testimony whereof I affix my signature in the presence of two witnesses.

CHRISTOPHER M. SPENCER.
